BELT SUPPORTED WATCH CARRIER

Julius H. Keller, Brooklyn, N. Y.

Application September 13, 1947, Serial No. 141,379

Term of patent 14 years

(Cl. D42—10)

To all whom it may concern:

Be it known that I, Julius H. Keller, a citizen of the United States, residing in the Borough of Brooklyn, the county of Kings, city and State of New York, have invented a new, original, and ornamental Design for a Belt Supported Watch Carrier of which the following is a specification, reference being had to the accompanying drawing, forming part thereof, wherein:

Fig. 1 is a perspective view of a belt supported watch carrier, showing my new design, the broken line showing of a belt being for illustrative purposes only and the same is omitted from the other figures for convenience of illustration;

Fig. 2 is a rear elevation;

Fig. 3 is a side elevation; and

Fig. 4 is also a rear elevation of the disclosure in Fig. 2 but in a partly open position.

I claim:

The ornamental design for a belt supported watch carrier, substantially as shown and described.

JULIUS H. KELLER.
